UNITED STATES PATENT OFFICE.

CARL HANS VOM BAUR, OF NEW YORK, N. Y.

AUTOMATIC STARTING DEVICE FOR ALTERNATING-CURRENT VAPOR-LAMPS.

No. 870,141.

Specification of Letters Patent.

Patented Nov. 5, 1907.

Application filed April 16, 1907. Serial No. 368,547.

To all whom it may concern:

Be it known that I, CARL HANS VOM BAUR, a citizen of the United States, residing at New York city, Manhattan, county and State of New York, have invented 5 new and useful Improvements in Automatic Starting Devices for Alternating-Current Vapor-Lamps, of which the following is a specification.

This invention relates to an alternating current mercury vapor lamp, and more particularly to improved 10 means for starting such lamp in a simple and reliable manner. By my invention the protracted manipulation heretofore necessary for starting lamps of this character is obviated, the lamps being automatically rocked by closing a circuit, until the ignition is effected, 15 after which the rocking motion is automatically discontinued.

In the accompanying drawing: Figure 1 is a diagram illustrating a mercury vapor lamp provided with my improved starting mechanism; Fig. 2 a detail cross 20 section through one end of the lamp; Fig. 3 a detail horizontal section through the mercury switch, and Fig. 4 a cross section on line 4-4, Fig. 3.

The numeral 10 indicates a vacuum tube suspended by hangers 11 in such a manner that it may be rocked 25 on its axis in manner hereinafter described. The ends of tube 10 are provided with enlargements 12 and 13, of which enlargement 12 has four seals which consist of platinum wire hermetically sealed in the glass and projecting beyond both sides thereof. Numerals 30 14 and 15 designate the main positive electrodes or anodes, which consist of small cups of suitable metal, such as iron, and which are fused to two of the platinum sealing-in-wires. 16 is an auxiliary negative electrode or cathode, consisting of mercury. In proximity to 35 cathode 16 is arranged an auxiliary anode 17, consisting of a separate body of mercury. Enlargement 13 is provided with the main mercury cathode 18.

Vapor lamp 10 receives single phase alternating current from the main or line wires 19, 20, by means of a 40 double pole switch 21, which, in turn, by wires 22, 23, is connected to an auto-transformer 24. The latter transforms the voltage of the main current to such as is best adapted for economically operating the lamp. One end of transformer 24, is, by wire 25, connected to anode 45 14, while the other end thereof is, by wire 26, connected to anode 15. The middle point of transformer 24 is, by wire 27, connected to a balance or steadyng resistance 28, which, in turn, by wire 29 is connected to an induction coil 30 encircling a non-laminated or solid iron 50 core 30a. From the latter a wire 31 leads to cathode 18. Opposite one end of coil 30 is arranged an armature 32 pivoted at 33. Weight 34 serves to hold the latter against a contact 35, which, by wire 36, is connected to wire 25. Armature 32 is, by wire 37, connected to a 55 contact 38 against which arm 39 of a bell-crank lever 39, 40 rests. The latter is by wire 41 connected to an al-

ternating current electro-magnet 42 which, in turn, by wire 43, is connected to transformer 24. Within electro-magnet 42 is mounted an axially reciprocating armature or core 44. The insulated upper hook-shaped 60 end 45 of armature 44 is adapted to engage arm 40 of bell-crank 39, 40. The lower end of armature 44 is connected to a metal arm 46 of tube 10 by a link 47. Opposite to armature 32, there is arranged in proximity to induction coil 30, the iron armature 48 of a 65 mercury switch 49. The latter consists of an arc-shaped glass tube partly filled with mercury, and provided at its ends with contacts 50, 51, projecting into the interior of the tube. When tube 49 is placed in a horizontal position, a metallic connection is thus established between wires 50, 51, while, when tube 49 is raised at its center by armature 48, (Fig. 4), said metallic connection is interrupted. Contact 50 is, by wire 52, connected to wire 31, while contact 51 is, by wire 53, connected to a limiting resistance 54, which is, in turn, by 75 wire 55, connected to cathode 16. Auxiliary anode 17 is, by wire 56 and starting resistance 57, connected to wire 26.

In order to start the lamp, switch 21 is closed, so that alternating current will flow from one end of transformer 80 24 through wires 25, 36, contact 35, armature 32, wire 37, contact 38, lever arm 39, wire 41, alternating current magnet 42 and wire 43, to the other end of transformer 24. In this way electro-magnet 42 is energized, and by attracting its core 44, will turn tube 10 on its 85 axis by link 47 and lever 46. When core 44 arrives near its highest position, hook 45 will engage arm 40 of lever 39, 40. The latter will thus be tilted to break contact between contact 38 and arm 39, and thereby open the circuit previously established. In this way 90 magnet 42 becomes disengaged to thereby release core 44 and permit the same to descend by gravity. The descent of armature 44 will turn tube 10 back into its original position.

The above described rocking movement of tube 10 95 has the following function: During the upward movement of core 44 and the resulting rotation of tube 10, part of the mercury in cathode 16 will flow over bridge 58 intermediate cathode 16 and anode 17, and come into metallic contact with anode 17. In this way a 100 circuit will be closed, the current flowing from transformer 24, through wire 26, resistance 57, wire 56, anode 17, cathode 16, wire 55, resistance 54, wire 53, contact 51, switch 49, contact 50, wires 52, 31, coil 30, wire 29, resistance 28, and wire 27, to the middle point 105 of transformer 24. As soon as core 44 arrives at its highest position, and tube 10 comes to a standstill, the flow of mercury from cathode 16 to anode 17 will be interrupted, whereby the metallic connection between cathode 16 and anode 17 is broken and an arc formed. 110 During the subsequent downward movement of core 44, mercury will flow from anode 17 to cathode 16, to re-

establish the circuit above described. At the end of this movement, the circuit is again interrupted, to again form an arc. In this way the lamp starts to rectify the alternating current, the positive being the parts 5 14 and 15, while the negative is cathode 16. If, upon breaking the arc between electrodes 16 and 17, due to the rocking motion of the lamp, no rectified current will flow, the previously described rocking motion of tube 10 is automatically repeated to again form an arc 10 between electrodes 16 and 17. This operation will be automatically continued until the arc formed becomes the means for starting the rectified current flowing between anodes 14, 15, and cathode 16. As soon as the current is rectified in the lamp, the alternating current 15 previously flowing through induction coil 30 will also be replaced by continuous current. It is evident that the amperage of the alternating current is considerably smaller than that of the direct current due to the fact that the alternating current is greatly cut down by impedance of the circuit. As the magnetizing force of an 20 electro-magnet is in direct proportion to the number of ampere-turns, it will be seen that alternating current has less effect than continuous current upon core 30. When continuous current flows through coil 30, armatures 32 and 48 will be immediately attracted by core 30. By attracting armature 48, switch 49 will be 25 raised into the position shown in Fig. 4, to disconnect cathode 16 from transformer 24. As soon as coil 30 has attracted armatures 32, 48, its energy is released and 30 its inductive force will "kick" through tube 10 to start an arc and light the lamp, the current traveling alternately from transformer 24 through wire 25, to anode 14, and through wire 26, to anode 15, and thence through tube 10, cathode 18, wire 31, coil 30, wire 29, 35 steady resistance 28, and wire 27, to the middle point of the transformer. The formation of the arc between anodes 14, 15 and cathode 16, is greatly facilitated as mercury vapors have already been produced in the lamp during the rocking period of the same. 40 The attraction of armature 32 by coil 30, will break the current previously flowing through magnet 42, so that the rocking motion of the lamp is stopped.

The advantages of my improved alternating current mercury lamp are numerous. The lamp is started by 45 simply closing a switch, without the necessity of manipulating a string for tilting the lamp, etc. Furthermore, if the main current is interrupted for any reason, or its voltage falls considerably, so that the lamp stops burning, it is automatically re-started as soon as the 50 current again becomes normal. Furthermore, as but

a slight rocking movement is imparted to the lamp for starting the same, the mercury does not receive any heavy shocks, so that the seals are not liable to be broken.

I claim:

1. In a device of the character described, a vacuum tube having a pair of positive main electrodes, a negative main electrode, a positive auxiliary electrode, and a negative auxiliary electrode, combined with automatic means for rocking the tube, substantially as specified. 55
2. In a device of the character described, a vacuum tube having a pair of positive main electrodes, a negative main electrode, a positive auxiliary mercury electrode, and a negative auxiliary mercury electrode, combined with automatic means for rocking the tube, whereby the contact 60 between the mercury electrodes is made or broken, substantially as specified. 65
3. In a device of the character described, a vacuum tube having a pair of positive main electrodes, a negative main electrode, a positive auxiliary mercury electrode, and a negative auxiliary mercury electrode, combined with a magnet having a core operatively connected to the tube, and automatic means for alternately energizing and de-energizing said magnet, substantially as specified. 70
4. In a device of the character described, a vacuum tube having a main cathode at one end, a pair of main anodes, an auxiliary anode and an auxiliary cathode at the other end, combined with a magnet having an armature operatively connected to the tube, a circuit for energizing said magnet, means controlled by the armature for breaking and closing said circuit, and independent means controlled by the lamp-current for breaking said circuit, substantially as specified. 75
5. In a device of the character described, a vacuum tube having a main cathode at one end, a pair of main anodes, an auxiliary anode and an auxiliary cathode at the other end, combined with a magnet having an armature operatively connected to the tube, a first switch in circuit with the magnet, a second circuit adapted to produce an arc between the auxiliary anode and the auxiliary cathode, a second switch controlling said second circuit, and means controlled by the lamp-current for operating both switches, substantially as specified. 85
6. In a device of the character described, a vacuum tube having a main cathode at one end, a pair of main anodes, an auxiliary anode and an auxiliary cathode at the other end, combined with automatic means for rocking the tube to produce an arc between the auxiliary anode and auxiliary cathode, a first switch controlling said means, a second switch in circuit with the auxiliary anode and auxiliary cathode, and means controlled by the lamp-circuit for opening both switches, substantially as specified. 95

Signed by me at New York city, (Manhattan,) N. Y., this 15th day of April, 1907.
